UNITED STATES PATENT OFFICE.

JOHN E. STOLTZ, OF CHARLESTON, WASHINGTON.

INDICATING AND ATTACHING DEVICE FOR SUNKEN SHIPS.

1,384,412.

Specification of Letters Patent. Patented July 12, 1921.

Application filed May 14, 1920. Serial No. 381,371.

To all whom it may concern:

Be it known that I, JOHN E. STOLTZ, a citizen of the United States, residing at Charleston, in the county of Kitsap and

5 State of Washington, have invented new and useful Improvements in Indicating and Attaching Devices for Sunken Ships.

My invention relates to improvements in such devices, wherein a pair or a plurality 10 of pairs of buoys are oppositely located on the deck of a ship, each pair connected by a line operating upon a reel contained in each buoy, said line extending through an inner portion of the hull and slidably engaged 15 therein so that when the ship is sunken and the buoys are afloat a cable may be connected with the line and drawn through the hull by the reel on one of the buoys, thereby securing a cable through the 20 hull and above the water on each side of the ship for lifting purposes.

The accompanying drawing illustrates my invention, and wherein—

Figure 1 is a front elevation of a buoy, 25 with a section partly cut away, showing a compartment containing cork and a reel carrying a line, the lower portion of the figure showing in longitudinal section the upper portion of a way for the line, said 30 way provided with a flaring opening adjacent the reel.

Fig. 2 represents in cross-section the double hull of a ship; a pair of buoys oppositely located on each side and a tube between 35 the walls of the hull adapted to carry a line connected with the reels of the buoys.

Fig. 3 illustrates the method of fastening said tube to the walls of a ship.

The apparatus provides a plurality of 40 pairs of buoys designed to be placed on the deck of a ship and oppositely located at the sides, Fig. 1 being illustrative of one of the buoys. It comprises a casing 1, which may be of any suitable form. Within the casing 45 are a number of watertight compartments shown at 2, filled with cork as illustrated at 3, sufficient to give the requisite buoyancy. 4 is a ring to facilitate handling of the device on deck, or for attaching a tow 50 line. 5 is a reel, carrying a line, rotatably mounted in the lower part of the casing as shown at 6, the portion 7 at its free end being of a form adapted to be engaged by a crank for handling the reel and line. The 55 compartment of the buoy containing the reel is provided at its upper portion with the

wall 8 of a strength sufficient to keep water away from the cork; the lower portion is open, the sides of the casing, however, having at the ends a contour which will fit into and rest upon complementary portions of a flaring end of the line way. 9 is a strip of rubber or other suitable material to make a close contact between the buoy and 10, one end of the line way. The line way 11, 65 through which the line or cable 12 is adapted to slide, is located in the ship substantially as shown in Fig. 2. This figure illustrates a hull provided with double walls, with a line way consisting of a tube extending 70 between the walls and terminating at each end in flared openings. These openings will be located slightly above the deck, and the buoys placed on the openings as illustrated in the figures. Said flared openings are designed to accommodate the operation of a line or cable on the reels. The tube will be fixedly attached to the outer walls by bands riveted to the walls and extending around the tube in such a way as 80 to give to the tube and its fastenings considerable resistant strength against the upward pull of a cable. In Fig. 3 is shown a section of the tube as held in place on the wall of a ship, the band 13 being preferably of iron or steel, and securely riveted or bolted to said wall. While Fig. 2 illustrates a ship with double walls, the device can be as well applied to one with single walls, and the tube attached in a similar manner. 90

In utilizing the apparatus, I contemplate the use ordinarily of two or more pairs of buoys, with their corresponding line ways, the number to be governed by the size or weight of the vessel. With the flared terminals close to a deck which will permit the buoys to rise in case of submergence, the buoys are placed on the terminals as shown in the illustrations. Should a ship sink, the buoys will rise to the surface, there being 95 sufficient length of line in the buoys to provide for any depth from which a ship could be salvaged. The buoys floating on the water will then indicate the location of the ship. When it is desired to raise the ship, 100 a cable possessing sustaining power commensurate with the size of the ship will be attached in a suitable manner to the line connecting each pair of buoys, said cable being drawn through the line way 11 in the 110 ship, by turning the reel on the opposite buoy. In this manner a lifting or sustain-

ing cable is secured within the hull of the ship and extending up on either side.

I claim:

An apparatus of the class described, comprising in combination with a ship, a plurality of pairs of buoys oppositely located on a deck of said ship, each buoy having a casing, within the casing a plurality of watertight compartments carrying cork, below said compartments another compartment having rotatably mounted therein a reel carrying a line, the lower end of said second compartment being open and provided with inturned angular sections along

its edge, a way for the line located adjacent the walls of the hull and extending around the interior of same, provided with fastenings having resistive strength against lifting and flared terminals opening out on said deck, each of said terminals adapted to afford a seat for the inturned angular sections of one of said buoys, a pair of said buoys located on the terminals and a line connecting the reels of said pair and slidably engaged through said way, means for reeling the line from either of said pair of buoys and through the line way.

JOHN E. STOLTZ.
